UNITED STATES PATENT OFFICE.

JAMES R. McALISTER, OF HAILESBORO, NEW YORK.

FIREARM.

No. 804,255.

Specification of Letters Patent.

Patented Nov. 14, 1

Application filed April 28, 1904. Serial No. 205,953.

To all whom it may concern:

Be it known that I, JAMES R. McALISTER, a citizen of the United States, residing at Hailesboro, in the county of St. Lawrence and State 5 of New York, have invented a new and useful Firearm, of which the following is a specification.

This invention relates to firearms of that general class in which an auxiliary barrel is 10 detachably mounted on the ordinary barrel; and the main object of the invention is to provide an auxiliary barrel of simple construction which carries its own breech block and lock and does not in any manner interfere 15 with or necessitate change in the construction of any portion of the firearm to which it is attached.

A further object of the invention is to provide an auxiliary barrel that may be quickly 20 placed in position or removed and one which may be made and sold as a separate article of manufacture to be applied to existing firearms.

A still further object of the invention is to 25 provide a novel form of barrel having a swinging breech-block which supports the firing-pin and all of its operating mechanism.

A still further object of the invention is to provide a simple form of securing device for 30 holding the auxiliary barrel to an ordinary single-barrel firearm.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, 35 proportions, size, and minor details of the structure may be made without departing from the spirit or sacrificing any of the advantages of the invention.

In the accompanying drawings, Figure 1 is 40 a side elevation of a portion of a firearm provided with an auxiliary barrel constructed in accordance with the invention. Fig. 2 is a similar view of a portion of the same, taken from the side opposite that shown in Fig. 1. Fig. 3 is a plan view showing principally the breech end of the auxiliary barrel. Fig. 4 is a detail perspective view of the breech-block detached. Fig. 5 is a view similar to Fig. 4, illustrating the construction of the breech end 45 of the barrel. Fig. 6 is a sectional plan view of the breech-block. Fig. 7 is a transverse

sectional view on the line 7 7 of Fig. 1, illustrating means for locking the auxiliary barrel in place.

Similar numerals of reference are employed to indicate corresponding parts throughout several figures of the drawings.

The auxiliary barrel is shown as applying a well-known type of single-barrel gun, including a barrel 1 and stock 2. The auxiliary barrel 4 is secured in place by clips 3, which are bent at both ends to partly embrace the barrels 1 and 4, said clips being connected in pairs by screws 3', the attachment being of such a simple nature that a person may readily place the auxiliary barrel in position or remove the same. The breech block 5 is provided with a forwardly-extending arm 7, which fits in a slight recess formed in the under surface of the barrel and is connected to said barrel by a pivot stud or screw 9, so that the breech-block may be removed to open or closed position. The breech end of the barrel is provided with a rearwardly-extending arm 14, forming 50 technically a continuation of the barrel, and terminates in an inwardly-extending rib 15, the rear wall of which is slightly tapered, and the front wall of said rib forms a straight slider in a plane at right angles to the end of the barrel. One side of the breech-block is slightly cut away, forming a recess 16, at the rear end of the recess is formed a rib 17 of a shape corresponding to the rib 15, adapted to receive the same, while the depth of the recess is about equal to the thickness of the arm 14, so that when the breech-block is closed the sides of the barrel and block are in a continuous line.

From that side of the breech-block opposite the recess 16 extends an arm 10, that terminates in an inwardly-projecting rib 11, the side of the barrel is provided with a recess 12 and a notch 13, adapted, respectively, to receive the rib and arm, the depth of recess in this case being also equal to the thickness of the arm. When the breech-block is closed, the two ribs will enter two notches, and the opposite sides of the block will thus be firmly held and rearward movement of the block prevented. It should be observed that the breech end of the barrel and the forward end of the breech-block are arranged on slightly-curved lines, so that there will be no difficulty in swinging the block to open or closed position.

At one side of the breech-block is pivoted

lever 18, that may be turned on its end 19 until its forward edge engages the side of the barrel and retains the closed position.

Breech-block is provided with an axial slot for the passage of a firing-pin 20, projected by a spring 21, the spring 21 tending to force the pin in the direction of the cartridge. The side wall of the breech-block is provided with an elongated slot 23, through which extends an arm 22, which may be grasped by hand in order to draw the firing-pin back, in other words, to cock the weapon. The forward end of the breech-block carries a trigger 25, having a sear-nose 26, which engages the arm 22 and holds the firing-pin to the rear. The free end of the trigger extends rearward and downward to a position adjacent to the main trigger-guard, convenient to the fingers of

In firing it is merely necessary to turn the trigger backward, the sear-nose rising into contact with the arm 22 and permitting the previously-compressed spring to move the firing-pin against the primer of the cartridge. This trigger further serves the purpose of a breech-operating lever, inasmuch as it may be grasped to throw the breech-block into closed position.

The top of the breech-block is pivoted at a point 27 in the form of a simple lever. As the forward end laterally extended, the lever may be turned so that the exertion comes into contact with the trigger 25 and prevents movement of the trigger to release the firing-pin, thus preventing accidental explosion of the cartridge.

Thus described the invention, what it is—

un-barrel provided at its breech-end with an axially-extending arm terminating in a laterally-projecting rib, the opposite end of the barrel being notched and recessed, the breech-block having a similar arm and rib, the notched and recessed, the arm and rib member being adapted to enter the opening of the other during movement of the breech-block, and a lever carried by said breech-block.

An auxiliary barrel for a firearm, a breech-block at the breech end of the barrel, a firing-pin carried by the breech-

block and provided with a laterally-extending arm, and a trigger pivoted to the breech-block and extending down to a position adjacent to the main trigger-guard of the weapon, said trigger being provided with a sear-nose for engaging the arm.

3. In an auxiliary barrel for a firearm, a breech-block at the breech end of the barrel, a spring-pressed firing-pin carried by the breech-block and provided with a laterally-extending arm, and a trigger pivoted at a point adjacent to the front end of the breech-block, the rear end of said trigger being extended to a position adjacent to the main trigger-guard, said trigger being provided with a sear-nose for engagement with the arm, the trigger serving further as a lever for swinging the breech-block to open and closed positions.

4. In a firearm, an auxiliary barrel, a breech-block having a forwardly-extending arm pivoted to the under side of the barrel, the mating faces of the breech-block and breech-end of the barrel being disposed on lines struck from the pivot-point of the arm, and both the barrel and the block being provided with engaging portions, a pivoted lever carried by the breech-block and serving by engagement with the barrel to prevent opening movement, a firing-pin carried by said breech-block, a spring tending to move the same to firing position, an arm projecting from the firing-pin, and a trigger pivotally connected to the breech-block and provided with a sear-nose for engaging said arm.

5. The combination in a firearm, of an auxiliary barrel, a breech-block pivotally connected thereto, a spring-pressed firing-pin carried by the breech-block, an arm projecting from the firing-pin, a trigger pivotally connected to the breech-block and having a sear-nose for engaging the arm, the lower and rear end of said trigger terminating at a point adjacent to the main trigger-guard of the firing-arm, and a safety device in the form of a lever pivoted to the top of the breech-block and adapted to engage and hold said trigger.

In testimony that I claim the foregoing as my own I have hereto affixed my signature in the presence of two witnesses.

JAMES R. McALISTER.
